US00D619733S

(12) **United States Design Patent**
Mugge et al.

(10) **Patent No.:** **US D619,733 S**
(45) **Date of Patent:** **** Jul. 13, 2010**

(54) **MOLDED SURFACES OF A CONCRETE PRODUCT**

(75) Inventors: **Jimmie L. Mugge**, Inver Grove Heights, MN (US); **Jay J. Johnson**, Star Prairie, WI (US)

(73) Assignee: **Anchor Wall Systems, Inc.**, Minnetonka, MN (US)

(**) Term: **14 Years**

(21) Appl. No.: **29/312,876**

(22) Filed: **Nov. 18, 2008**

(51) LOC (9) Cl. **25-01**

(52) U.S. Cl. **D25/113**

(58) Field of Classification Search **D25/102,**

(57) **CLAIM**

The ornamental design for molded surfaces of a concrete product, as shown and described.

DESCRIPTION

FIG. 1 is a front view of an embodiment of a concrete product, according to our new design, the portions shown in broken lines forming no part of the design sought to be patented;

FIG. 2 is a right side view of the concrete product of FIG. 1, the portions shown in broken lines forming no part of the design sought to be patented;

FIG. 3 is a left side view of the concrete product of FIG. 1, the portions shown in broken lines forming no part of the design sought to be patented;

FIG. 4 is a top view of the concrete product of FIG. 1, the portions shown in broken lines forming no part of the design sought to be patented;

FIG. 5 is a bottom view of the concrete product of FIG. 1, the portions shown in broken lines forming no part of the design sought to be patented;

FIG. 6 is a perspective view of the concrete product of FIG. 1, the portions shown in broken lines forming no part of the design sought to be patented.

FIG. 7 is a front view of a second embodiment of a concrete product, according to our new design, the portions shown in broken lines forming no part of the design sought to be patented; and,

FIG. 8 is a right side view of the concrete product of FIG. 7, the portions shown in broken lines forming no part of the design sought to be patented.
